UNITED STATES PATENT OFFICE.

JULES DOLDER, OF GREVENBROICH, GERMANY.

APPARATUS FOR MERCERIZING.

SPECIFICATION forming part of Letters Patent No. 642,899, dated February 6, 1900.

Application filed March 24, 1899. Serial No. 710,283. (No model.)

To all whom it may concern:

Be it known that I, JULES DOLDER, engineer, a citizen of Switzerland, residing at Grevenbroich, in the Empire of Germany, have invented certain new and useful Improvements 5 in Mercer Dyeing-Machines, of which the following is a specification.

This invention relates to machines for mercerizing yarn in skeins; and the object of the 10 invention is to provide a machine in which the operations of stretching, dyeing, and washing the skeins, besides other accessory operations, will be automatically performed so as to coact to produce the best results in the finished article.

The invention consists in the improved 15 Mercer dyeing-machine and in the combination and arrangement of its various parts, substantially as will be hereinafter pointed out, 20 and finally embodied in the clauses of the claim.

The invention is fully illustrated in the accompanying drawings, wherein—

Figure 1 is a view in side elevation of my 25 invention. Fig. 2 is a front view of my improved Mercer dyeing-machine, certain parts being removed. Fig. 3 is a view of a certain 30 guide for imparting oscillations to one of each pair of rollers which carry the skeins, so that in the resultant oscillation of this roller the tension on the skein will be for a time varied. Figs. 4 and 4^a show a pair of the rollers, a modified 35 form of one of them for intermittently varying the tension on the skeins being illustrated. Fig. 5 illustrates hoods for closing in the skeins and the rollers carrying them while the former are undergoing the washing operation and also showing means for automatically actuating the hoods. Figs. 6 and 7 illustrate 40 the mechanism for controlling the water-supply and the stopping device for the machine, and Fig. 8 illustrates the mechanism for imparting motion to the rotating frame, the same being shown in top plan view.

In said drawings, g' g^2 are two uprights, which may be braced in any desired manner and which provide bearings for the main drive-shaft c^5 , carrying drive-pulleys c^6 . Mounted upon the shaft c^5 is a pair of spiders 45 d' d^2 , which afford bearings for a series of stub-shafts concentrically arranged therein about the shaft c^5 and carrying rollers a' a^6 . In said

spiders are also journaled other shafts h , which are bent into the shape of cranks and whose free ends afford bearings for other rollers b' b^6 , 55 the other end of each of these shafts h being provided with a crank h' , having a crank-pin k . Upon the inside of the upright g' and adjacent the cranks h' is secured a disk M , having a circular groove or slot M' in its exposed 60 face. With the slot M' communicates another slot N , which is deflected inwardly toward the center of the disk and connects with the slot M' at both its ends. Hinged deflectors Q' Q^2 are pivotally secured in an operative position 65 at the junctures of the two slots. It will be seen that as the spiders are rotated, therefore, the crank-pins k will either follow the circular slot or the slot N , according as the deflector Q' is closed or opened. It should be re- 70 marked that the deflectors Q' Q^2 may be maintained in their open or closed positions in any desired manner and that they are adapted to be manually operated.

Beneath the series of rollers there is suit- 75 ably supported a tank X , adapted to receive the dyeing liquid. This liquid is fed from a siphon-pipe c^1 , communicating with a tank c^8 , which is supplied by a pump c^9 , said pump being operated by a lever c^{10} , to which is connected a pitman c^{11} , that is pivoted to and receives a reciprocating motion from a wheel c^{12} , which is driven from the main shaft by a system of belts c^{13} c^{14} and pulleys c^{15} c^{16} . The several parts just referred to are all shown 85 in dotted lines in Fig. 1.

d^5 is a suitably-fulcrumed pair of spring-actuated levers carrying a roller ST , the disposition of the roller relatively to the revolving series of skeins being such that as the latter approach it said roller is forced against the skeins, its function being to press or wring out as much of the free dyeing liquid as possible.

The machine is surmounted by a washing 95 apparatus. This apparatus consists of a pipe d^7 , which extends over the series of rollers in a plane contiguous, preferably, to that of their highest elevation, and a valve d^8 , controlling said pipe and supported upon a standard d^9 , that surmounts the upright g' . The valve-stem of the valve d^8 is connected to a lever d^9 , that is fulcrumed at one of its ends in a standard d^{10} , resting upon the top of the

framework of the machine, the free end of said lever being pivotally connected to a weighted fork d^1 , carrying a roller d^2 , which bears upon the periphery of a notched disk 5 K. The fork is guided in a bracket d^3 , which projects outwardly from the standard d^9 . It will be seen, of course, that as the disk K revolves the fork will be periodically actuated to effect the opening and closing of the valve 10 d^8 , controlling the water-supply. The disk K is revolved by a train of gearing K', (shown in Fig. 6 of the drawings,) said train of gearing being connected to the shaft c^5 . It should be remarked that the extremity of the pipe 15 d^7 extends over the entire width of the skeins and is provided with spraying-orifices, as shown in Fig. 5. The discharge portion of the pipe may be divided, as also shown in Fig. 5, into two or more branches.

20 It has been already intimated that the stub-shafts a^1 a^6 are revolvably supported in the spiders d^1 d^2 . Said stub-shafts carry pulleys s , and over these pulleys extends a belt T, which also extends over a small pulley t , that 25 is mounted upon one end of a shaft t' , journaled in the upright g' and carrying another pulley t^2 at its other end. In Fig. 2 the shaft t' is shown as having a portion thereof broken away. The pulley t^2 , and consequently the 30 pulleys t and s , which it controls, are operated from the main drive-shaft through a driving mechanism comprising the pulley u of said drive-shaft, pulleys u' and u'' , journaled to upright g' , the belt u^4 , connecting 35 pulleys u and u' , and a belt u^3 , connecting pulleys u'' and t^2 . The belt t is maintained taut by a tension device consisting of a weighted lever v , that is fulcrumed in the frame and whose end is provided with a roller 40 v' , which bears against the belt T under the action of the weight on the lever.

50 V is a stop-lever fulcrumed in the upright g' and extending upwardly, where its free end is adapted to be engaged by a cam Z, disposed upon one face of the disk K. From the fulcrum end of this lever projects a detent V' , which as the lever falls when released by the cam assumes a position in the path of a projection C, which extends from the bearing of 55 each stub-shaft a^1 a^6 in the spider d^1 .

The several stub-shafts are surrounded and immediately engaged by a metallic ribbon o , which is secured so taut that it requires some exertion to rotate the several stub-shafts in 60 their bearings—that is to say, sufficient exertion so that so long as the spiders are free to rotate on the shaft c^5 the belt will act to turn said spiders and both series of shafts they carry without individually rotating the 65 several stub-shafts, whose pulleys, it will be observed, in effect act as practically immovable bearing devices for the engagement of the belt t . When, however, the stop-lever is permitted to fall, so that the detent will engage one of the projections C, the spider will be prevented from rotating, and hence the

belt t can act to rotate the several pulleys s individually.

Disposed above the main shaft c^5 is the reservoir A for catching the water that falls off the skeins in the washing operation. In order to prevent the water from being thrown from the skeins over the end edges of this reservoir and down into the dyeing-tank and onto the subjacent skeins, hoods E are provided, the same being supported in suitably-fulcrumed levers A' A^2 , which are connected by a pitman A^3 and one of which is provided with an arm A^4 , that is adapted to be engaged by a cam A^5 upon the disk K. As the 80 disk revolves its cam A^5 is adapted to strike against the arm A^4 , and thus elevate the hoods to permit the pairs of rollers carrying the skeins to successively take a position beneath them and move out from under them. 85

It should be remarked that the disposition of the notch in the periphery of the disk K and of the two cams A^5 and Z on said disk should be such that the several parts which they initially control will be made to properly coact—that is to say, said notch and the cam should be so disposed that the rotation of the spiders will be stopped and the supply of water for washing the skeins cut off while the skeins are in position for the washing operation and while they are assuming this position, respectively.

The roller which I show in Figs. 4 and 4^a consists of an iron body or core L, which is mounted upon the stub-shaft, and a cylinder 100 P, having a series of longitudinal ribs upon its outer surface, which in an obvious manner effect intermittent stretching of the skeins as the pair of rollers revolve and the skein is wound around them. This intermittent 105 stretching of the skeins is designed to facilitate their proper impregnation with the dyeing liquid.

Assuming that the frame comprising the two spiders rotates in the direction of the arrow shown in Fig. 1, so long as the detent V' does not engage one of the projections C the belt t will act to revolve the frame and all of the skein-carrying rollers, bringing each skein successively under the action of the dyeing 115 apparatus. Intermittently, as hereinbefore described, the detent V' is actuated to stop the movement of the frame, and while the frame is therefore at rest certain of the skeins are being dyed, others are being brushed or 120 scoured by the attendant, (as, for instance, the one above the wringing mechanism,) others are being washed, while still others are in a position for removal by the operator, having passed through the several steps necessary to 125 finish them. During each intermittent partial revolution of the frame the skeins carried on the pair of rollers which are adjacent to the roller-carrying levers d^6 are wrung out by the roller which these levers carry, so as to relieve them of as much of the dyeing liquid as possible. Of course while the frame is at a

standstill, moreover, and as hereinbefore described, the several rollers a' a^6 are being rapidly rotated, thus materially facilitating the proper performance of the dyeing-washing and other operations. It should be remarked, however, that by providing the deflected slot N in the disk M the crank-pins can be made to oscillate the bent shafts which carry the rollers b' b^6 , so that at the point where the skeins are removed from the machine the tension thereon will be relieved. If it is desired that each skein should pass more than once through the several operations, instead of opening the deflectors Q' Q^2 , as in the case when it is desired to immediately remove the skeins, the attendant closes them, thus shutting off the passage through the deflected slot, and consequently maintaining the tension on the skein.

Having thus fully described my invention, what I claim as new, and desire to secure by Letters Patent, is—

1. In a dyeing-machine the combination with a revoluble frame, of roller-carrying shafts, journaled in said frame, a taut belt or band surrounding and bearing upon said shafts, pulleys carried by said shafts, a pulley journaled independently of said revoluble frame, a belt connecting all of said pulleys, means for operating the last-named pulley, and means for intermittently stopping the rotation of said frame, substantially as described.

2. In a dyeing-machine, the combination with a pair of uprights, of a revoluble frame, a shaft journaled in said uprights and providing a bearing for said frame, stub-shafts journaled in said frame, a taut band surrounding and bearing upon said stub-shafts, pulleys carried on said stub-shafts, a pulley mounted independently of said revoluble frame, a belt connecting all of said pulleys, an operative connection between the drive-shaft and said last-named pulley, bent oscillatory shafts having bearings in said revoluble frame, means for oscillating said bent shafts, an intermittently-acting detent adapted to engage said revoluble frame to stop the rotation thereof, and operative connecting means between the drive-shaft and said detent, substantially as described.

3. In a dyeing-machine, the combination with a pair of uprights, of a revoluble frame, a shaft journaled in said uprights and providing a bearing for said frame, stub-shafts journaled in said frame, a taut band surrounding and bearing upon said stub-shafts, pulleys carried on said stub-shafts, a pulley mounted independently of said revoluble frame, a belt connecting all of said pulleys, an operative connection between the drive-shaft and said last-named pulley, bent oscillatory shafts having bearings in said frame, means for oscillating said bent shafts, a lever fulcrumed in one of said uprights, an intermittently-acting detent carried by said lever and adapted to engage said frame to stop the rotation thereof,

a cam-disk journaled in said upright, said lever being adapted to engage the cam on said disk, and an operative connection between said cam and said drive-shaft, substantially as described.

4. In a dyeing-machine, the combination, with a pair of uprights, of a revoluble frame, a drive-shaft journaled in said uprights and providing bearings for said frame, roller-carrying shafts journaled in said frame and adapted to receive the article to be dyed, a suitably-supported receptacle, hoods extending over said receptacle, operatively-connected levers fulcrumed in one of said uprights and carrying said hoods, means for rotating said frame and said roller-carrying shafts, a detent adapted to intermittently engage said frame to stop the rotation thereof, a lever fulcrumed in one of said uprights and carrying the detent, a revoluble disk operatively connected to said first-named shaft and carrying cams, said disk being journaled in one of the uprights, and an arm projecting from one of said hood-carrying levers and adapted to be engaged by one of the cams, another of said cams being adapted to engage said detent-carrying lever, substantially as described.

5. In a dyeing-machine, the combination, with a pair of uprights, of a revoluble frame, a drive-shaft journaled in said uprights and providing bearings for said frame, roller-carrying shafts journaled in said frame and adapted to receive the article to be dyed, a suitably-supported receptacle, hoods extending over said receptacle, operatively-connected levers fulcrumed in one of said uprights and carrying said hoods, means for rotating said frame and said roller-carrying shafts, a detent adapted to intermittently engage said frame to stop the rotation thereof, a lever fulcrumed in one of said uprights and carrying the detent, a revoluble disk operatively connected to said first-named shaft and having a notch in its periphery and carrying cams, an arm projecting from one of said hood-carrying levers and adapted to be engaged by one of the cams, another of said cams being adapted to engage said detent-carrying lever, a water-supply, a feed-pipe communicating therewith and having its discharge disposed beneath said hoods, a valve controlling said pipe, and an actuating device for said valve operatively connected thereto and wiping on the periphery of said disk, substantially as described.

6. In a dyeing-machine, the combination with a pair of uprights, of a revoluble frame, a shaft journaled in said uprights and providing a bearing for said frame, devices carried by said revoluble frame for supporting the articles to be dyed, a receptacle suitably supported by said uprights, operatively-connected levers journaled in one of said uprights, hoods carried by said levers and disposed over said receptacle, an arm carried by one of said levers, a revoluble disk mounted

- in one of said uprights and having a cam adapted to engage said arm, and gearing connecting said revoluble disk and said shaft, substantially as described.
- 5 7. In a dyeing-machine, the combination with a pair of uprights, of a revoluble frame mounted in said uprights, revoluble shafts mounted in said frame and carrying rollers for the reception of the articles to be dyed, a taut band surrounding and bearing upon said shafts, pulleys carried by said shafts, a pulley mounted independently of said revoluble frame, a belt connecting all of said pulleys, means for actuating the last-named pulley, 15 and a weighted lever fulcrumed in one of said uprights in proximity to said belt and provided with a roller bearing against the same at a point between two of said pulleys, substantially as described.
- 20 8. In a machine for dyeing yarn in skeins, the combination, with a pair of uprights, of a revoluble frame journaled in said uprights, spaced roller-carrying shafts mounted in said frame, each pair of said shafts being adapted 25 to receive and maintain taut the skeins, a spring-actuated pair of levers fulcrumed in operative proximity to said frame, and a roller carried by said levers and adapted to bear upon the skeins as the frame revolves, substantially as described. 30
9. In a dyeing-machine, the combination with a revoluble frame, stub-shafts journaled in said frame, bent shafts also journaled in said frame, said shafts carrying rollers for receiving the articles to be dyed, 35 of a disk supported independently of said revoluble frame and in proximity to one side of the latter, and having a circular slot or groove and also a deflected slot communicating at both ends with said circular slot, said 40 bent shafts having eccentric engagement with said slots, and deflectors carried by said disk controlling the communication between said slots, substantially as described.

In testimony that I claim the foregoing I 45 have hereto set my hand this 3d day of March, 1899.

JULES DOLDER.
